TABLE

Morton R. Cohen, 5490 S. South Shore Drive,
Chicago, Ill.

Filed Jan. 20, 1958, Ser. No. 49,318

Term of patent 14 years

(Cl. D33—14)

Fig 1 is a perspective view of a table showing my new design;

Fig. 2 is a front elevational view of the same on an enlarged scale;

Fig. 3 is a side elevational view of the same; and

Figs. 4 and 5 are, respectively, fragmentary front and side elevational views on a greatly enlarged scale to show decorative details of the design.

The dominant features of my invention reside in those portions shown in full lines on the drawing.

The legs not shown are like the leg shown but are indicated in broken lines for illustrative purposes only.

I claim:

The ornamental design for a table, substantially as shown and described.
